UNITED STATES PATENT OFFICE.

MARIUS JEAN BAPTISTE BARBAROU, OF NEUILLY-SUR-SEINE, FRANCE.

ELECTROMAGNETIC IGNITION SWITCH FOR INTERNAL-COMBUSTION ENGINES.

Application filed August 20, 1920. Serial No. 404,856.

To all whom it may concern:

Be it known that I, MARIUS JEAN BAPTISTE BARBAROU, a citizen of the Republic of France, residing at Neuilly-sur-Seine,

5 in the Republic of France, have invented new and useful Improvements in Electromagnetic Ignition Switches for Internal-Combustion Engines, of which the following is a specification.

10 It is the customary practice to carry out the ignition of explosion motors by the use of a magneto.

But in the case of motor starting devices it is not an easy matter to obtain the proper 15 starting, by reason of the slow initial speed given to the explosion motor by the starter.

It is in fact recognized that a minimum speed of 60 to 70 revolutions per minute is required for the motor in order to obtain 20 a suitable spark from the magneto, said minimum speed being the absolute speed at the moment of the occurrence of the compression, i. e., of the ignition.

However in the case of a motor of mean 25 or high power, it becomes impossible to provide a starter having a sufficient capacity together with a storage battery suitable for supplying the same, whereby the said minimum speed of 60 to 70 revolutions shall 30 be obtained under all circumstances at the moment of occurrence of the compression.

On the other hand, the fact that a storage battery is provided for the lighting and for motor starting will afford a convenient 35 means for employing an ignition distributor supplied by a high tension coil.

This invention has for its object to utilize the high tension spark coil, which produces a constant spark at all speeds of the motor, 40 to provide for the ignition upon starting the motor, while the magneto will secure the ignition at normal speed. These two operations are carried out in an automatic manner by the use of an apparatus termed 45 "permutator", which is the object of this invention.

In the accompanying drawings which are given by way of example:

Fig. 1 is a longitudinal axial section of 50 an ignition permutator constructed according to this invention.

Fig. 2 is a corresponding plan view.

Fig. 3 is an end view of the left hand side of the same.

55 Fig. 4 is an end view of the right hand side.

Fig. 5 is a diagrammatic view indicating the various electric connections between the permutator and the cooperating members of the ignition device.

60

As represented in the drawing, the ignition permutator according to this invention comprises essentially a metal casing having disposed therein the magnetic field member *b* of an electro-magnet, the disk-like armature *c* whereof is movable axially. The said armature is secured to a central core *d* having the internal portion thereof constituted of an insulating substance *e*. The other end of the core is provided with a 70 rounded stud *f*.

65

The movable assemblage of the electromagnet is returned to the inoperative position by means of the spring *g*.

75

The magnet coil *h* is constituted by a winding having one end thereof connected to the metal framework the other end being connected to the terminal *i* by the lug *j*. The terminal *i* is mounted upon the cover *k* constructed of insulating material.

80

At the other end of the casing *a* is inserted a block *l* of insulating substance having disposed thereon the three terminals *m*, *n*, *o*.

85

A cut out portion in the block *l* contains swinging therein the rocking member *p* also of insulating material.

A metal cross pin *q* serves as a pivot for the same.

90

The rocking member *p* is provided upon its opposite sides with the two flat contact strips *r*¹, *r*².

95

The strip *r*¹ is in constant contact with the terminal *m* through the medium of the coil'd spring *s*, while the strip *r*² is maintained in constant connection with the terminal *n* by means of the spring blade *t*.

The contact member *u* is on the other hand connected to the terminal *o*.

100

The terminal *o* is connected to the ignition distributor *D* (Fig. 5) supplying the spark plugs, the terminal *n* is connected to the high tension spark coil *C* supplied by the battery *Z*, and the terminal *m* is connected to the magneto *B*. Connection is also made between the terminal *i* of the electro-magnet coil and a suitable terminal *v* on the high tension coil *C* whereby the current of the battery *Z* is supplied at the same time to the electro-magnet of the permutator *A* 105 and the spark coil *C*.

105

The connections are properly made by 110

The connections are properly made by

means of a combination switch W whose handle x is operated by the driver of the vehicle.

Y is the line connected to the generator.

5 The said handle is adapted to take three positions, viz:—

1—Full stop.

2—Operating with magneto.

10 3—Operating with high tension spark coil for the starting.

Under the above conditions, the operation of the permutator is as follows:

In the normal position for the motor running with magneto, the switch being in 15 the position numbered 1, the contact strip r^1 of the rocking member is in constant contact with the contact member u, whereby constant connection is provided between the terminal o and the terminal m, i. e., between 20 the magneto B and the distributor D.

At the moment of starting, with the handle placed in the position "start" (numeral 3 of the diagram), the current is sent into the electro-magnet h of the permutator 25 whereupon the movable armature will be attracted and the stud f will exert a pressure upon the rocking member g, causing this latter to swing. At the end of the stroke, the strip r^2 will come in turn in contact 30 with the member u. At this moment, by reason of the spring contact member t, electric connection will be made between the terminal n and the terminal o, i. e., between the high tension coil C and the distributor 35 D. The starter is put in action and the explosion motor will now rotate.

As soon as this latter commences running

by its own means, the switch handle is placed in the position "magneto" (numeral 2 of the diagram).

The connection is now broken between the electro-magnet of the permutator A and the battery Z on the one hand, and the spark coil C and the battery Z on the other hand.

The springs s and g will add their effect 45 to drive back the movable armature, and the rocking member now assumes its normal position, whereby the magneto B is connected to the ignition distributor D. The ignition is thus definitely effected by the 50 magneto B alone.

Having now described my invention, what I claim as new and desire to secure by Letters Patent is:

An ignition electromagnetic switch comprising a casing, an energizing coil therein, a spring controlled core slidable axially through said coil and provided at one end with an insulating member, a rocker adapted to be operated by said insulating member, said rocker having a rounded end, parallel contact blades separate from each other on said rocker, one of said blades extending over said rounded end, a fixed contact member with which said contact blades are 55 adapted to alternately contact, a returning coiled spring adapted to convey an electric current to one contact blade, and a spring blade in constant contact with the rounded 60 part of the other contact blade and adapted to convey an electric current to the same 65

In testimony whereof I have signed my name to this specification.

MARIUS JEAN BAPTISTE BARBAROU.
